UNITED STATES PATENT OFFICE.

ROY W. LELLIS AND EUGENE W. ADAMS, OF TORONTO, ONTARIO, CANADA, ASSIGNEES
OF ONE-THIRD TO FREDERICK P. HAMBLY, OF TORONTO, CANADA.

GAME APPARATUS.

1,386,517.

Specification of Letters Patent.

Patented Aug. 2, 1921.

Application filed October 7, 1920. Serial No. 415,318.

To all whom it may concern:

Be it known that we, ROY W. LELLIS and EUGENE W. ADAMS, subjects of the King of Great Britain, residing in the city of Toronto, in the county of York, Province of Ontario, Canada, have invented certain new and useful Improvements in Game Apparatus, of which the following is a specification.

10 This invention relates to amusement or game devices such as are largely employed in popular amusement resorts, our object being to provide an improved game table designed especially for playing the game of 15 baseball and which will automatically record on an indicator board "the length of hit made by the batter."

A further object is to provide simple and easily operated means for clearing the 20 device of balls when a game is over.

The device is constructed as hereinafter described and illustrated in the accompanying drawings in which—

Figure 1 is a plan view, partly diagrammatic, of the apparatus;

Fig. 2 a section on the line *a—a* in Fig. 1; and

Fig. 3 is a sectional detail showing the method of establishing the electrical contact 30 in one of the holes.

In the drawings like numerals of reference indicate corresponding parts in the different figures.

1 is a saucer shaped playing board suitably supported on a stand 2. In the bottom 3 of the saucer are formed a plurality of holes 4 of sufficient size to allow the balls used in playing the game to pass through them. The bottom 3 and the holes therein 40 will usually be laid out in the form of an ordinary baseball diamond.

To prevent the balls dropping through the holes 4 on to the ground, a ball support 5 is provided below the bottom 3. This support 5 will usually be hinged at one side, as at 6, and will be retained in its ball supporting position by means of a lever 8 fulcrumed on an upright 9, which lever 8 will preferably have an anti-friction roller 50 7 journaled on the end engaging the ball support 5. This lever 8 might, however, be suitably fulcrumed on the stand 2. Means will be provided for locking the lever 8 with its roller 7 in the raised position. A 60 trough 10 is preferably secured on the

frame 2 to receive the balls from the support 5 and guide the balls to a receptacle 11.

Supported on the ball support 5 are a plurality of electrical contacts 12. Each of these contacts will be directly underneath 60 a hole 4, and will comprise two spring members, the end of one of the members extending over the end of the other, but normally out of contact with each other. At least the upper member of the contact 12 is of sufficient 65 lightness and flexibility that the weight of one of the balls used with the apparatus will be sufficient to depress the upper member so that it will contact with the lower member.

As in the present case, only certain of the holes, such as 4^a, 4^b, 4^c, and 4^d, representing first base, second base, third base and the home plate, have values placed thereon, contacts 12 will usually only be placed under 70 these particular holes.

In conjunction with the device, we provide an indicator board 14, which will usually be laid out as a baseball diamond to correspond with the bottom 3. On this indicator board will be supported a plurality of lights. A light 15^a will be connected with the contact below the hole 4^a, a light 15^b connected with the contact below the hole 4^b, a light 15^c connected with the contact below the hole 4^c, and a light 15^d will be connected with the contact below the hole 4^d.

It will be understood, of course, that contacts 12 may be provided under each hole 4 90 and a corresponding light placed on the indicator board 14 for each contact, and in this case the holes having special values might have their corresponding lights in 95 distinguishing colors.

The apparatus will be used as follows. Each player will be provided with a ball. As the holes 4^a, 4^b, 4^c, and 4^d, which indicate the bases are given graduated values, for example, a one base hit, a two base hit, a 100 three base hit, and a home run respectively, it will be the players' object to throw the balls into the holes having the highest values. Preferably all the players will throw their balls simultaneously, and the player whose ball landed in the hole 4^d would be declared the winner, or if no ball landed in the hole 4^d, the player whose ball landed in the hole 4^c, 4^b or 4^a, as the case may be, would be the 105 winner. The weight of the balls in the holes 110

4^a, 4^b, 4^c, and 4^d resting on the contacts 12 beneath them would close the circuits of the lights 15^a, 15^b, 15^c and 15^d, which would then be illuminated.

5 The balls would, of course, have to have suitable identifying marks, such as the name of a city, a numeral or letter, or be of different colors.

When the game is ended, the lever 8 is unlocked, which allows the ball support 5 to swing down and the balls roll off into the trough 10, and thence into the receptacle 11. The ball support 5 is then again raised into position by the lever 8, the lever locked, and 15 the apparatus is then in condition for the next game.

It will be understood of course that the different light circuits may each include a separate source of current, or connected up 20 to one source as is the most convenient.

What we claim as our invention is:—

1. In game apparatus, the combination of a board having a plurality of openings therein large enough for the passage of balls; a 25 common movable ball support located below said board and adapted to retain balls in said openings; releasable means for holding the ball support in ball supporting position, and a trough adapted to receive balls from 30 the ball support when the latter is moved from its ball supporting position.

2. In game apparatus, the combination of a board having a plurality of openings there-

in; a common ball support located below said openings and adapted to retain balls therein; 35 an electrical contact located on said support below one of said openings; an indicator board; an electrical circuit including a source of power, a light on said indicator board, and said contact, said circuit being 40 adapted to be closed to operate the light by a ball resting on said contact.

3. In game apparatus, the combination of a board having a plurality of openings therein; a frame supporting said board; a 45 movable support located below said board and adapted to support balls in said openings; releasable means for holding the ball support in ball supporting position; electric contacts located on the movable support 50 directly below certain of said openings; an indicator board having lights thereon corresponding to the holes having electric contacts; an electric circuit for each of said lights including a source of current and the 55 contact, said circuits being adapted to be closed to operate the lights by balls resting on said contacts.

Signed at the said city of Toronto this 25th day of September, 1920.

ROY W. LELLIS.
EUGENE W. ADAMS.
